UNITED STATES PATENT OFFICE.

GEORGE LUDWIG, OF MILWAUKEE, WISCONSIN, ASSIGNOR TO MOE-BRIDGES COMPANY, OF MILWAUKEE, WISCONSIN, A CORPORATION OF WISCONSIN.

DESIGN FOR A LIGHTING FIXTURE.

Application filed June 27, 1923. Serial No. 6,597. Term of patent 7 years.

To all whom it may concern:

Be it known that I, GEORGE LUDWIG, a citizen of the United States, residing in Milwaukee, in the county of Milwaukee and State of Wisconsin, have invented a new, original, and ornamental Design for Lighting Fixtures, of which the following is a specification, reference being had to the accompanying drawing, forming part thereof.

The figure is a view of a lighting fixture showing my new design.

I claim:

The ornamental design for a lighting fixture, as shown.

GEORGE LUDWIG.
